[57] CLAIM

The ornamental design for the light beam clock, as shown and described.

DESCRIPTION

FIG. 1 is a top and right front perspective view of a light beam clock showing my new design;

FIG. 2 is a front elevational view thereof;

FIG. 3 is a rear elevational view thereof;

FIG. 4 is a right side elevational view thereof, the left side being a mirror image thereto;

FIG. 5 is a top plan view thereof;

FIG. 6 is a cross-sectional view as taken from line 6—6 of FIG. 4;

FIG. 7 is a cross-sectional view as taken from line 7—7 of FIG. 4.

FIG. 1

FIG. 2

FIG. 3

FIG. 4

FIG. 5

FIG. 6

FIG. 7
